(57) CLAIM

The ornamental design for a combined television receiver and video disc player, as shown and described.

DESCRIPTION

FIG. 1 is a perspective view of the top, front and right side of a combined television receiver and video disc player showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a view similar to FIG. 1 with the disc receiving drawer extended.
